CLAIM

The ornamental design for a connector, as shown and described.

DESCRIPTION

FIG. 1 is a top, front, isometric view of the connector; FIG. 2 is a front, plan view thereof; the right, left, and back plan views being a mirror image thereof;

FIG. 3 is a top, plan view thereof; and,

FIG. 4 is a bottom, plan view thereof.

The broken lines depict portions of the connector and form no part of the claimed design.
